Patented Oct. 14, 1919.

UNITED STATES PATENT OFFICE.

HUGH W. CHRONIC, OF SANDPOINT, IDAHO.

WINDOW-LOCK.

1,318,965.

Specification of Letters Patent.

Patented Oct. 14, 1919.

Application filed January 23, 1919. Serial No. 272,731.

To all whom it may concern:

Be it known that I, HUGH W. CHRONIC, a citizen of the United States, residing at Sandpoint, in the county of Bonner and State of Idaho, have invented certain new and useful Improvements in Window-Locks; and I do hereby declare the following to be a full, clear, and exact description of the invention, such as will enable others skilled in the art to which it appertains to make and use the same.

This invention relates to window locks, and more particularly to means for securing a window sash in adjusted position.

15 One of the main objects of the invention is to provide simple and efficient means which may be readily applied to a window sash of standard construction adapted to lock the sash in adjustment and to permit it to be 20 readily adjusted in either direction.

A further object is to provide a securing rod and locking levers associated therewith and carried by the window sash, these levers being so related as to normally prevent 25 movement of the sash in either direction and being adapted to be readily moved into inoperative position so as to permit the sash to be adjusted.

Further objects will appear from the detailed description.

In the drawings:

Figure 1 is a front view of a window securing means constructed in accordance with my invention as applied.

35 Fig. 2 is a front view of the lock proper with the top plate removed.

Fig. 3 is a side view of the same.

Fig. 4 is a section taken substantially on line 4—4 of Fig. 3.

40 Fig. 5 is a view similar to Fig. 4 showing one of the locking levers in inoperative position.

In applying my invention, I provide a lock designated generally by 1 which is secured 45 to the side rail 2 of a window sash 3 slidably in frame 4 of standard construction, this lock coöperating with a locking rod 5 secured to the adjacent side member of the window casing. This rod 5 is disposed vertically and 50 projects into a vertically extending groove 6 formed in the rail 2 for this purpose, the end portions of the rod being offset and flattened to provide securing ears 7 which receive screws 8 inserted therethrough and 55 screwed into the casing.

The lock includes a flat base plate 9 which

carries a substantially rectangular housing 10 the side walls 11 of which are provided with inwardly directed transversely extending stop members 12 the inner ends of which 60 are rounded and are spaced equidistant from a centrally positioned post 13 of substantial rectangular cross section which is disposed with its faces substantially at forty-five degrees to the edges of base plate 9 so as to provide, in effect, knife-edge bearings at each side directed toward the adjacent inner ends 65 of the stop members 12. As will be noted more clearly from Fig. 2 the innermost edges of the members 12 are positioned slightly in 70 advance of the lateral edges of post 13 so as to provide forwardly converging passages or slots which receive locking levers 14 inserted therebetween. These levers are provided, adjacent their outer ends, with cylindrical 75 openings 15 which receive the body portion of rod 5, this rod being inserted through openings provided through the side walls of housing 10, adjacent the outer ends thereof, for this purpose. The edges of post 13 and 80 the stop members 12 provide fulcrums for rocking movement of the levers in either direction transversely of the housing, these levers being normally held with their outer ends rocked inwardly into contact at the center of the outer edge of base plate 9 by expansion coil springs 16 mounted about rod 5 and confined between the outer end portions 85 of the levers and walls 11. Inward movement of the levers, toward each other, is positively limited by a securing screw 17 which is inserted through the housing 10 and base plate 9, this screw cooperating with securing screws 18 inserted through flanges 19 projecting laterally of the base plate 9 to secure 90 the lock in position. In practice, the locking rod 5 is secured to the window casing in the manner stated and projects into groove 6, the lock being mortised into the side rail 2 with the inner end portions of the levers 14 95 projecting beyond the inner edge of this rail so as to be readily accessible.

When the locking levers are in normal position with their outer ends in engagement, as in Fig. 4, the material of the levers 105 at the diagonally opposite inner and outer edges of the openings 15 engage rod 5, as shown. If it is attempted to move the window sash, and consequently the lock, in either direction, the levers at the inner edges 110 of these openings are forced into biting engagement with rod 5 so as to positively pre-

vent movement of the window, the outer edges of the openings being also forced into biting engagement with the rod. If it is desired to lower the sash, the inner end of the lower lever 14 is raised so as to bring this lever into engagement with the stop screw 17, thus bringing the openings 15 into concentric relation with rod 5. With the lower lever in this position, the window may be readily lowered, as the spring 16 of the other lever will permit sufficient upward give of the outer end thereof to prevent binding on rod 15. When it is desired to raise the window, the upper lever is similarly operated. By grasping both levers simultaneously and forcing them toward each other, at their inner ends, so as to bring the openings 15 into concentric relation with rod 5, the window sash may be freely moved in either direction, being positively locked in adjustment upon release of the levers.

It will be evident that there may be slight changes made in the construction and arrangement of the details of my invention without departing from the field and scope of the same, and I intend to include all such variations, as fall within the scope of the appended claim, in this application in which a preferred form only of my invention is disclosed.

What I claim is:

In window securing means, a lock including a housing adapted to be secured to the side rail of a window sash, said housing being provided adjacent each side with an inwardly extending stop member, a bearing post carried by the housing between the inner ends of said stop members and equidis-

tant therefrom, the stop members and bearing post forming spaced passageways for reception of locking levers, locking levers inserted through said passageways at each side of the post and being provided with openings adjacent their outer ends, said post being provided with laterally directed bearing edges and the stop members being provided with bearing edges positioned outwardly beyond the bearing edges of the post, each of said levers being provided with an opening therethrough adjacent its outer end, a locking rod inserted through the side walls of the lock housing and through said openings of the levers, said rod being of less diameter than the openings in the levers and being adapted to be secured to a window casing, and expansion coil springs mounted about said rod and confined between the side walls of the housing and the outer ends of the levers, said springs acting to normally hold the outer ends of said levers toward each other so as to maintain the levers at the edges of said openings thereof in biting engagement with said rod, the bearing post and the stop members being so related as to permit the levers to be rocked into such position as to bring the openings therethrough into substantial concentric relation with the rod so as to permit movement of the window sash in either direction desired.

In testimony whereof I affix my signature in presence of two witnesses.

HUGH W. CHRONIC.
